UNITED STATES PATENT OFFICE.

GEORGE W. COMBS, OF LEAVENWORTH, KANSAS.

CONTROLLING MEANS FOR GYRATORY STRUCTURES.

1,142,146.

Specification of Letters Patent.

Patented June 8, 1915.

Application filed August 28, 1911. Serial No. 646,321.

To all whom it may concern:

Be it known that I, GEORGE W. COMBS, a citizen of the United States, residing at Leavenworth, in the county of Leavenworth and State of Kansas, have invented certain new and useful Improvements in Controlling Means for Gyratory Structures, of which the following is a specification.

My invention relates to improvements in controlling means for gyratory structures, such as sifters and the like, and my primary object is to provide new and useful means of this character which will automatically adjust itself to the variable speeds and loads to which the structure is subjected, and thus tend to restrain said structure from abnormal lateral or orbital movement and render its action more uniform. My improved means is, preferably, wholly arranged between the boxes of the structure, instead of at the ends thereof, consequently, access may be had to the driving mechanism and bearings of the structure during the operation thereof without danger of being struck, which is likely to occur where the customary rigid type of unbalancing weights are employed above and below the structure. A further advantage in placing my device wholly between the boxes instead of at the top and bottom thereof, resides in the fact that it is out of the way of the spouts entering and leaving the boxes.

In order that the invention may be fully understood, reference will now be made to the accompanying drawings, in which:

Figure 1 is a side elevation of a gyratory sifter structure provided with my invention. Fig. 2 is a broken side elevation of the sifter structure provided with my invention, the latter being in vertical section. Figs. 3 and 4 are cross sections of the invention on lines III—III and IV—IV, respectively, of Fig. 2. Fig. 5 is a broken side elevation of a sifter structure, provided with a modified form of the invention, and Fig. 6 is a cross section of the invention on line VI—VI of Fig. 5.

I have shown the invention applied, in the present instance, to a sifter structure em-

bodying sifter boxes 1, united at their upper 50 and lower ends by spiders 2 and 3, and freely suspended for gyration by a plurality of reeds 4.

Spiders 2 and 3 have centrally-disposed bearings 5 and 6, respectively, to support a 55 centrally-disposed vertically-positioned shaft 7, having oppositely-extending tapered upper and lower portions 8 and 9, respectively.

10 and 11 designate two sleeves mounted on the tapered portions 8 and 9 of shaft 7, 60 to which they are keyed or otherwise fixed for rotation therewith, said sleeves being provided with hubs 12 and 13, mounted upon bearings 5 and 6, which latter have lubricant chambers 14 and 15, respectively, to hold a 65 supply of lubricant for the bearings 5 and 6.

Sleeves 10 and 11 are further secured to shaft 7 by a connecting-rod 16, having right and left threaded-terminals engaging internally-threaded bosses 17 and 18 on the 70 sleeves 10 and 11, respectively. By turning the connecting-rod 16 in one direction, the sleeves will be firmly drawn toward each other upon the tapered portions 8 and 9 of the shaft, so that there can be no lost motion 75 between these parts. After the sleeves have been firmly drawn upon the tapered portions of shaft 7, the connecting-rod 16 is held from accidental turning by a pair of jam-nuts 19, mounted on the threaded portions 80 of the rod, and adapted to abut against the bosses 17 and 18.

20 designates a drive pulley having a ball-and-socket connection 21 with a stem 22 supported by an overhead bearing 23. 85

24 designates a universal coupling having an eccentric portion 25 fixed to the upper end of shaft 7, to permit the latter to move in an orbit with the sifter structure.

26 designates a pin fixed to the hub of 90 pulley 20 by a set-screw 27 and having a groove-and-feather connection 28 with the universal coupling 24. By thus yieldingly-mounting pulley 20 upon stem 22, binding of the former upon the latter is averted should 95 the building containing the structure settle, and the ball-and-socket connection 21, in conjunction with the universal coupling 24

and pin 26 affords a yielding-connection whereby shaft 7 is driven and permitted to move orbitally with the structure when the same is gyrating. The groove-and-feather connection 28 permits of slight independent longitudinal movement between pin 26 and coupling 24, should the structure gyrate abnormally.

Shaft 7 is caused to move in an orbit to gyrate the structure, and the orbital path is automatically determined by my improved controlling means, consisting of an elongated weight or member 29, and a plurality of links or members 30, which latter are pivotally-secured at their free ends to the former by pins 31, and pivotally-secured at their opposite ends to the sleeves by pins 32. Pins 31 are secured from lateral displacement by a pair of screw-plugs 33, screwed into member 29 and abutting against the ends of the pins.

Member 29 consists preferably of a heavy weight and is segmental in cross section, to prevent its ends from striking the adjacent sides of boxes 1, between which it is wholly arranged to be out of the way of spouts A and B entering and leaving said boxes. Member 29 has a plurality of pockets 34 to receive supplemental weights 35, the number of which may be increased or diminished to properly balance the structure, said weights being removably-secured in place by bolts 36 and nuts 37.

Links 30 are preferably of equal length to hold member 29 parallel with shaft 7, so that when the same is at rest, member 29 will hang close to the shaft, and since it is desirable to have the center of gravity of said member as nearly as possible, in coincidence with the axis of shaft 7, I form a longitudinal groove 38 at the central portion of the inner side of the member to receive the adjacent side of the shaft, and having a recess 39 in sleeve 11 to receive the lowermost pin 31.

When shaft 7 and my improved controlling means are rotated, centrifugal force causes member 29 to swing outward and upward from the shaft, and thus impart gyroscopic motion to the latter and to the structure. The extent of outward and upward movement of member 29 depends on the speed at which the structure is driven, and thus automatically tends to restrain the structure from lunging or traveling in an abnormal path; whereas if the member were fixed a predetermined distance from the shaft, it would cause the structure to lunge when starting and stopping, and at such times when the structure was not traveling at normal speed, or subjected to variable loads.

The modified form of controlling means disclosed by Figs. 5 and 6 is substantially

the same in construction and operation as 65 the preferred form, the chief difference residing in applying the greater portion of the weight to links 30^a instead of to member 29.

Referring in detail to Figs. 5 and 6, 1^a designates the sieve boxes of the structure, which are connected by spiders 2^a and 3^a, having centrally-disposed bearings for the vertically positioned shaft 7^a. 10^a and 11^a designate sleeves keyed to shaft 7^a and united by a connecting-bar 16^a. 30^a designates links 7^a pivotally-connected to the sleeves by pins 32^a and having enlarged weighted ends 29^a, united by a member 29^b pivotally-connected thereto by pins 31^a, to cause said weighted ends 29^a to operate in unison. Pins 31^a are secured from lateral movement by screw-plugs 33^a engaging the opposite ends thereof.

Having thus described my invention, what I claim, and desire to secure by Letters Patent, is:

1. In combination, a gyratory structure, a journaled shaft thereto adapted to gyrate therewith, and means to control gyratory motion of said shaft and the structure, consisting of an elongated member, and means movably connecting said member to the shaft at a plurality of points.

2. In combination, a gyratory body, a shaft thereto capable of orbital movement, and means to control orbital movement of said shaft consisting of an elongated member, and pivotal means operably-connecting said elongated member and the shaft at a plurality of points.

3. In combination, a body, yielding means supporting said body for gyration, a shaft to said body, and means to control gyratory motion of the body, consisting of an elongated weight, and means capable of vertical movement connecting the weight and the shaft and adapted to retain said weight parallel with the shaft.

4. In combination, a body suspended for gyration, a shaft thereto capable of lateral movement in any direction, means to control gyratory motion of the suspended body consisting of a vertically elongated weight movably-connected to the shaft and provided with pockets, and supplemental weights removably arranged within said pockets.

5. In combination, a gyratory structure, a centrally-disposed shaft thereto, and means to control gyratory motion of the shaft consisting of an elongated member, and links operably-connecting said member and the shaft.

6. In combination, a gyratory body, a shaft thereto, sleeves fixed to said shaft, and means to control gyratory motion of the body consisting of a weighted member, and means pivotally connecting said weighted member and the sleeves.

7. In combination, a gyratory structure, a

journaled shaft thereto, yielding means to drive said shaft, and means parallel with said shaft adapted to swing toward and away from the same according to the speed of rotation, for the purpose described.

8. In combination, a gyratory structure, having centrally-disposed bearings, a shaft journaled in said bearings, an eccentric weight arranged wholly between said bear-

ings, and links operably connecting said weight and the shaft.

In testimony whereof I affix my signature, in the presence of two witnesses.

GEORGE W. COMBS.
